[57] CLAIM

The ornamental design for a solar oven, substantially as
shown and described.

DESCRIPTION

FIG. 1 is a perspective view of a solar oven taken in the
direction of use showing my new design;

FIG. 2 is a perspective thereof taken in the reverse
direction;

FIG. 3 is a top plan view thereof, shown with the oven
in an alternate position;

FIG. 4 is a rear elevational view thereof, on a slightly
smaller scale;

FIG. 5 is a front elevational view thereof, on the same
scale as used in FIG. 4;

FIG. 6 is a side elevational view thereof, on the same
scale as used in FIG. 4; and

FIG. 7 is a bottom plan view thereof on the same scale
as used in FIG. 4.
